UNITED STATES PATENT OFFICE.

EDWARD A. EVERETT, OF DETROIT, MICHIGAN.

ELECTRIC TRACK-CIRCUIT AND METHOD OF INSULATING SAME.

SPECIFICATION forming part of Letters Patent No. 726,269, dated April 28, 1903.

Application filed February 10, 1902. Serial No. 93,477. (No model.)

To all whom it may concern:

Be it known that I, EDWARD A. EVERETT, a citizen of the United States, residing at Detroit, county of Wayne, State of Michigan, have invented a certain new and useful Improvement in Methods of Insulating Electric Track-Circuits; and I declare the following to be a full, clear, and exact description of the invention, such as will enable others skilled in the art to which it pertains to make and use the same, reference being had to the accompanying drawings, which form a part of this specification.

My invention relates generally to insulating electric conductors, and more particularly to insulating the sections of railroad - rails forming portions of track-circuits.

In railroad signaling it is customary to utilize the rails of the track as portions of the circuits controlling the operation of the signals, the ends of the adjoining rails being electrically united by bonds. The imperfect insulation afforded by the ordinary wooden railroad-ties has rendered it impossible to use

an extended section of a rail as a portion of the electric conductor of a signal-operating circuit and has consequently restricted the utilization of the rail as a conductor to a comparatively limited section in each circuit.

The conductivity of the ties and ground is also increased by the dripping of salt water from refrigerating-cars upon the track, which saturates the ties and ground adjacent to the rails and renders still more imperfect the natural insulation of the rails, thereby in-

creasing danger of short-circuiting the track-circuits. The absence of insulation between the rails and the ties and ground underlying the rails also frequently results in the further objection that foreign currents of electricity, due, for instance, to the discharge of electricity to the earth from railways having electrically-propelled cars, flow through the track-circuits and operate the signals. An-

other difficulty which is experienced in the use of track-circuits for electrical signaling is due to the corroding and rapid deterioration of the bonds between the adjoining ends of the rails by the salt water which drips from refrigerating-cars.

The primary object of my invention is to render possible the use of longer sections of

railroad - rails as portions of the conductors of signal - circuits than has heretofore been practicable.

A further object is to reduce the liability of interference of foreign currents with the track signal-circuits.

A still further object is to prevent the corroding of the electric bonds between the adjoining rails forming parts of track-circuits.

A still further object of my invention is to protect the insulating material between the ends of the track-sections forming parts of electric circuits and the adjacent ends of the adjoining rails outside of the track-circuits, thereby preventing the insulation of the track-circuits being rendered inefficient during rainy weather.

I accomplish the above objects by interposing oil between the rails and the underlying ties and ground and by coating with oil the bonds connecting the adjoining rails.

My invention, generally stated, consists in a method of electrically insulating the rails of a railroad-track.

My invention further consists in a method of increasing the efficiency of track-circuits which consists in electrically insulating the rails from the ties and ground by interposing oil and in applying to the bond-wires thereof a protecting coat of oil.

My invention will be more fully disclosed hereinafter with reference to the accompanying drawings, in which the same is illustrated in a convenient and practical form, and in which—

Figure 1 is a perspective view of a portion of a rail and portions of ties thereunder; Fig. 2, a cross-sectional view through the rail and tie, the latter being broken away; and Fig. 3, a diagrammatic view of a track-circuit insulated according to my invention.

Similar reference characters indicate similar parts in the several figures of the drawings.

The following is a detail description of my invention.

The wooden ties A A, which underlie the rails B B, are treated with mineral or other suitable oil both beneath the rail and preferably, also, to a considerable distance either side of the rail. The ground between the ties and beneath the rails is also preferably coated.

with the oil for a distance on either side of the rail corresponding in extent to the portion of the ties covered with the oil, as indicated in Fig. 3. In carrying out my improved process the oil is applied to the webs and bases of the rails and also preferably to the ties and ground adjacent to the rails. The oil is applied in sufficient quantity, preferably to each side of the rail, to flow down the web and around the base. The vibration of the rail due to the passage of trains thereover permits the oil to work between the rail and the ties, thereby effectively insulating the rails. It has been found in actual practice that by applying the oil to only one surface of the web of the rail it will work its way completely under the base of the rail and appear on the opposite side thereof to that upon which it was applied, this action being due to the depression of the rail by the passage of a train and its subsequent slight elevation after the train has passed, thereby permitting the oil to pass beneath the base of the rail and which upon the passage of a subsequent train is forced in all directions between the under surface of the base of the rail and the tie.

The usual bonds, one of which is shown at C in Fig. 1, for electrically uniting the adjacent ends of the rails are also covered with oil in order to protect them from the corrosive effect of the salt water which drips from refrigerating-ears, and thereby prolong the life of the bonds. The oil may be applied to the bonds by a separate operation from that which insulates the rails. When, however, the bonds have been secured in place prior to the application of oil to the rails, one operation is sufficient both to cover the bonds with oil and to insulate the rails.

The source of electricity, which is ordinarily a track-battery D, is connected with the insulated section of rail by leads d in the usual manner. The relay or other translating device E is included in the conductor e, forming a portion of the circuit.

From the foregoing description of my invention it will be observed that I have invented an improved method for insulating the rails of a track-circuit and also for further increasing the efficiency of track-circuits by applying a protecting-coating to the bonds uniting the adjoining rails.

Having now fully described my invention, what I claim as new, and desire to secure by Letters Patent, is—

1. In the art of electrically insulating track-circuits, the process consisting in interposing substantially throughout the length of the circuit oil between the section of railroad-rails forming part of such circuit and the underlying ties and road-bed, by applying oil to the web and base of the railroad-rails.

2. The method of increasing the efficiency of an electric track-circuit which consists in applying substantially throughout the length of the circuit oil to the web and base of the section of railroad-rails forming part of such circuit, whereby the oil is interposed between the rails and the underlying ties and road-bed and whereby the bonds uniting adjoining rails are covered with a protecting coating of oil.

In testimony whereof I sign this specification in the presence of two witnesses.

EDWARD A. EVERETT.
